UNITED STATES PATENT OFFICE.

GEORGE F. CONNER, OF PORT HURON, MICHIGAN.

BEET-TOPPER.

No. 820,391.

Specification of Letters Patent.

Patented May 15, 1906.

Original application filed February 2, 1903, Serial No. 141,453. Divided and this application filed April 6, 1903. Serial No. 151,291.

To all whom it may concern:

Be it known that I, GEORGE F. CONNER, a citizen of the United States of America, and a resident of the city of Port Huron, county 5 of St. Clair, State of Michigan, have invented certain new and useful Improvements in Beet-Toppers, of which the following is a full, clear, and exact specification.

This invention relates to machines for top- 10 ping beets, and especially to means for accomplishing this before removing them from the ground.

Inasmuch as a topping mechanism which embodies the features of the invention is 15 easily adapted for use in conjunction with beet-pulling machines, it is hereinafter shown and illustrated in connection with such a machine. Obviously the puller may at the option of the user be of any preferred design. 20 As herein illustrated, I show a beet-pulling machine which is made the subject of my application for Letters Patent of the United States, Serial No. 141,453, filed February 2, 1903, of which this is a divisional application.

25 In the drawings, Figure 1 is a view in side elevation of a beet-harvester provided with a topping mechanism which embodies the principal features of the invention herein claimed, parts of the machine being broken away to give clear view. Fig. 2 is a view in front elevation of the topping device. Fig. 3 is a view in end elevation of the topping mechanism. Fig. 4 is a view in cross-section through a roller on line 4 4 of Fig. 2.

35 Referring to the drawings, A represents a beet-harvesting machine mounted on a pair of traction-wheels B. A part C of the frame of the machine, which extends forward of the mechanism, affords a convenient place for 40 the attachment of a draft-rigging. The beet-pulling means comprise rotatable members D, which are located between the traction-wheels and are adapted to furrow through the earth on both sides of a row of beets, said 45 members being driven by operative connection through sprockets E and F, chains G, and counter-shaft H to the shaft I of the traction-wheels B.

The topping mechanism proper is prefer- 50 ably secured to the beet-harvester in the following manner: A roller-frame J is secured to the beet-harvester forward of and in aline-

ment with the digging members. As herein indicated, a convenient place for attaching the device to a harvester of the kind shown is 55 on the draft-frame C. Said roller-frame J is supported by and rides on a truncated cone or roller, which is rotatively secured therein so that its axis of rotation lies in a plane transverse to the plane of the pulling mem- 60 bers D and to the path of motion of the machine, the frame preferably being provided with a vertical stem j, which may have longitudinal sliding engagement in a socket on the draft-frame C. Said cone or roller K is 65 mounted on a journal k, which rotates in suitable bearings j² in said frame J in such a position that its periphery rests on the ground the entire length of the roller. Said cone is 70 positively driven by suitable mechanism operatively connecting it to the traction-wheels of the beet-harvester, to which it may be attached. Owing to the position of the driving mechanism herein described, the connect- 75 ing means comprises a toggle-joint L, connecting the roller-journal k to a horizontal journal k², mounted in suitable bearings j³. A sprocket-wheel M and sprocket connec- 80 tions m drive the journal k² from the counter-shaft H of the beet-harvester.

In operation it is best to provide the roller-frame J with means for lifting it clear of the ground when it is desired to turn the machine around or move it from the field. As herein illustrated, such means comprises link and lever connections with a handle-bar N, which in this instance also raises the beet-pulling members in unison with the roller.

The roller or cone K traverses the ground just ahead of a cutter O, for which it acts as a 90 gage. The latter may be of any preferred design adapted to cut the tops of the beet off. Preferably it comprises a horizontal knife-blade secured at one end by an upturned stem o to the frame J, its cutting edge being disposed 95 obliquely to the path of travel of the machine slightly in rear of the roller K.

In addition to performing the office of a gage to the cutter the roller K is adapted to carry the beet-tops against and across the cutter, so as to give them a positive shearing movement thereon. In order to accomplish this result, the roller is positively rotated, so that its small end maintains normal rolling

- contact with the ground, or it may have a rate of speed higher than this. Instead of the mechanism herein shown for driving the cone its smaller end may be provided with spurs or 5 studs, which engage the ground and impart the required slipping contact of the major portion of the cone-surface or with the driving means. The efficiency of the roller is found to be increased by providing its 10 surface with a plurality of flutes P, extending transversely to the direction of motion of its periphery, the flutes gripping the leaves and drawing them over the knife more firmly than a smooth surface does.
- 15 In operation the cones gage the position of the knife or cutter so that the latter always tops the beets at a uniform height. Furthermore, the combined rolling and sliding movement of the cone draws the beet-tops in and 20 passes them back over the knife or cutter with a positive movement which insures their being severed. The peripheral speed is of course greatest at the largest end of the roll, which is forward of the advanced end of the 25 knife, and as a consequence the beet-tops are carried along the blade with a diagonal slipping motion toward its rear end, so that they fall outside of the line of action of the pulling members. This prevents the latter from becoming 30 clogged with the stalks and leaves and clears a space on the ground on which the beets may be deposited.
- While, as herein described, the coned roller is preferable as a gage, owing to the lateral 35 motion with which it sweeps across the cutter, other forms may be used, the cylindrical being perfectly feasible, provided it is not especially desired to move the leaves to one side; also, the roller may be used merely as a 40 gage, which likewise drags the tops across the cutter and holds the beet-crowns from breaking off before they are completely severed, other means being used to force the severed portions away from the knife.
- 45 It is apparent that beet-topping mechanism of this description may be mounted on traction-wheels and so operated independently of any beet-pulling mechanism, and I may use it so if I desire. It is adaptable for 50 use with any harvester which is mounted on traction-wheels, so that positive motion may be given to the roller, provided spurs or spuds are not used thereon.
- Obviously many details in the form and ar- 55 rangement of parts may be varied without departing from the spirit of the invention, and I do not limit myself to any particular form or arrangement of parts except as set forth in the appended claims.
- 60 I claim as my invention—
1. A beet-topper comprising a cutter, a gage for the cutter riding on the beet-crowns, and means for driving said gage, said gage

being adapted to coact with the cutter to shear off tops drawn between them by the 65 rotation of the gage.

2. A beet-topper comprising a fixed cutting-blade, a rotatable gage maintaining the cutter in the proper vertical relation to the beet-crowns and means for rotating the gage, 70 the surface of the gage being adapted to draw tops between the gage and cutter, and to coact with the cutter to shear them off.

3. A beet-topper comprising cutting means and a cone-roller gaging the vertical position 75 of the cutting means.

4. A beet-topper comprising cutting means and a positively-driven cone-roller gaging the vertical position of the cutting means.

5. A beet-topper comprising cutting means 80 and a cone-roller gaging the vertical position of the cutting means positively driven at a speed not less than the speed of its small end when said small end is maintaining normal rolling contact with the ground. 85

6. A beet-topper comprising cutting means, and a cone-roller traversing the ground in advance of the cutter adapted to maintain said cutter in proper vertical position and to draw beet-tops across the cutting 90 means.

7. A beet-topper comprising a vertically- 95 movable frame, a cutter secured thereto, and a coned roller journaled in said frame, in advance of the cutter, adapted to gage the vertical position of the cutter, and positively driven at a speed not less than the speed of its small end when the latter is maintaining normal rolling contact with the ground.

8. A beet-topper comprising a vertically- 100 movable frame, a cutter secured thereto, and a coned roller journaled therein slightly in advance of the cutter, adapted to gage the vertical position of said cutter, and means operatively connecting said cone to traction- 105 wheels, adapted to positively rotate said cone at a speed not less than the speed of its small end when the latter is maintaining normal rolling contact with the ground.

9. A beet-topper comprising a frame verti- 110 cally movable in a frame supported on traction-wheels, a coned rotatable roller supporting said frame by contact with the ground throughout its length, a cutter secured to said frame in close proximity to and behind 115 said roller, an adjustable universal-joint connection between said roller and a drive-wheel and operative connections between said wheel and the traction-wheels of the machine. 120

10. A beet-topper comprising a frame held in horizontal alignment in a frame supported on traction-wheels and vertically supported by a cone-roller journaled therein engaging with the ground, a cutter secured to said frame in close proximity to and behind said 125

roller, driving mechanism adapted to rotate said roller at a speed not less than the speed of its small end when the latter is maintaining normal rolling contact with the ground, 5 whereby said roller engages and carries beet-tops diagonally across the cutter and discharges them from the machine at the rearward end of said cutter.

In testimony whereof I have hereunto signed my name to this specification in the presence of two subscribing witnesses.

GEORGE F. CONNER.
